UNITED STATES PATENT OFFICE.

HENRY W. PARTON, OF YONKERS, NEW YORK, ASSIGNOR TO THE ALEX. SMITH & SONS CARPET COMPANY, OF SAME PLACE.

DESIGN FOR A CARPET.

SPECIFICATION forming part of Design No. 20,269, dated November 4, 1890.

Application filed October 10, 1890. Serial No. 367,626. Term of patent 3½ years.

To all whom it may concern:

Be it known that I, HENRY W. PARTON, a citizen of the United States, residing at Yonkers, Westchester county, New York, have invented a new and original Design for Carpets, of which the following is a specification, reference being had to the accompanying photograph, which forms a part of the same.

The invention relates to a design to be worked into or upon surfaces, such as carpets or similar fabrics; and it consists in the novel configuration and grouping of figures herein specifically shown and claimed.

The accompanying photograph is a face view of a carpet showing my new design.

My design consists of the body A and the border B. The body A is composed of irregular-shaped forms somewhat resembling water-lily and bud forms and a shaded groundwork of

forms resembling water-lily leaves under and around the lily-shaped flower forms. The border B is composed of a conventional inner margin, a central band of forms somewhat resembling water-lily and bud-shaped flower forms, and an outer margin of wavy lines of gem-shaped ornamentations.

What I claim as new, and desire to secure by Letters Patent, is—

1. The design for carpets, consisting of the body A, substantially as shown.
2. The design for carpets, consisting of the border B, substantially as shown.
3. The design for carpets, consisting of the body A and border B, substantially as shown.

HENRY W. PARTON.
